United States Patent Office.

PETER BLOOMSBURG, JR., AND JAMES MOLYNEUX, OF BORDENTOWN,
NEW JERSEY, ASSIGNORS TO BORDENTOWN MACHINE COMPANY.

Letters Patent No. 65,051, dated May 28, 1867; antedated May 16, 1867.

IMPROVEMENT IN MECHANICAL MOVEMENT.

The Schedule referred to in these Letters Patent and making part of the same.

TO ALL WHOM IT MAY CONCERN:

Be it known that we, JAMES MOLYNEUX and PETER BLOOMSBURG, Jr., both of Bordentown, Burlington county, New Jersey, have invented a new Mechanical Movement; and we do hereby declare the following to be a full, clear, and exact description of the same, reference being had to the accompanying drawing, and to the letters of reference marked thereon.

Our invention consists of certain mechanism, described hereafter, for transmitting from a single eccentric on a driving-shaft a positive rotary motion to another shaft.

In order to enable others skilled in machinery of the class to which this most nearly appertains to make and use our invention, we will now proceed to describe its construction and operation. On reference to the accompanying drawing, which forms a part of this specification—

Figures 1 and 2 are side views; and

Figure 3, a plan view of our mechanical movement; and

Figure 4 is a view of part of the same.

Similar letters refer to similar parts throughout the several views.

A is the driving-shaft, and A' the shaft, to which a rotary motion has to be imparted from the driving-shaft, and on the latter is an eccentric, B, embraced by the end b of the eccentric-rod C, the outer end of the latter being adapted to the pin f of the crank G on the end of the shaft A'. To this pin f is secured a plate, g, on which is a pin, h, adapted to receive the outer end of a rod, F, the inner end of which is jointed to the arm d' of a bell-crank lever, D, the latter being hung to a pin or shaft, C, secured to any stationary object. The arm d of the bell-crank lever D is connected by a link, E, to a pin, e, on a projection on the rod b of the eccentric-rod C. It will be seen, on reference to fig. 4, that a double crank is formed on the end of the shaft A', or, in other words, there are two cranks of equal length, one crank situated at right angles to the other. On turning the shaft A in the direction of its arrow the shaft A' will be turned in the same direction, the several parts moving in the direction pointed out by their arrows until the most projecting portion of the eccentric B passes the line x drawn through the centres of the two shafts A and A', after which the rods and levers will commence a movement in a direction contrary to that pointed out. As seen in fig. 1, the eccentric is exerting little or no power to turn the shaft A' through the medium of the crank G, as the latter occupies a position nearly coincident with the line x. The same eccentric, however, is exerting its full force to turn the shaft through the medium of the other crank. When one crank is on what is termed the dead-centre the other is always in the best position for acting as a medium for transmitting motion to the shaft A' precisely as in the crank-shaft of coupled marine engines.

In the present instance the movement is illustrated as being applied to the transmission of a motion from the crank-shaft to the rotating valves of a steam engine, but it will be evident that the device may be advantageously used in a variety of cases where a positive rotary motion has to be imparted from one shaft to another, especially when the shafts are at such a distance apart from each other as to render the introduction of cog-wheels cumbrous and costly.

What we claim as our invention, and desire to secure by Letters Patent, is—

The single eccentric B on the driving-shaft, the eccentric-rod C, lever D and rod F, in combination with the double crank on the driving-shaft, the whole being arranged and operating substantially as and for the purpose set forth.

In testimony whereof we have signed our names to this specification in the presence of two subscribing witnesses.

PETER BLOOMSBURG, JR.,
JAS. MOLYNEUX.
